UNITED STATES PATENT OFFICE.

LOUIS L. RAYNOR, OF NEW YORK, N. Y., ASSIGNOR TO THE PAGODA TEA COMPANY, INC., A CORPORATION OF NEW YORK.

DESIGN FOR A CONTAINER FOR TEA.

Application filed October 20, 1925. Serial No. 15,201. Term of patent 14 years.

To all whom it may concern:

Be it known that I, LOUIS L. RAYNOR, a citizen of the United States of America, residing at 500 West 140th Street, city, county, and State of New York, have invented a new, original, and ornamental Design for Containers for Tea, of which the following is a specification.

Figure 1 is an elevational view of a container for tea embodying my design; Fig-

I claim:

The ornamental design for a container for tea, as shown.

In testimony whereof I affix my signature.

LOUIS L. RAYNOR.
